R. M. McGAHEE.
DUST PROOF KNUCKLE JOINT.
APPLICATION FILED MAY 6, 1912.

1,054,015.

Patented Feb. 25, 1913.

UNITED STATES PATENT OFFICE.

RANDOLPHE MENALCUS McGAHEE, OF TAMPA, FLORIDA.

DUST-PROOF KNUCKLE-JOINT.

1,054,015.

Specification of Letters Patent. Patented Feb. 25, 1913.

Application filed May 6, 1912. Serial No. 695,510.

To all whom it may concern:

Be it known that I, RANDOLPHE M. McGAHEE, a citizen of the United States, residing at Tampa, in the county of Hillsboro and State of Florida, have invented a new and useful Dust-Proof Knuckle-Joint, of which the following is a specification.

One object of the present invention is to provide a device of the class above mentioned, having novel dust-excluding caps which prevent the entrance of dust at the ends of the knuckle.

A further object of the invention is to provide a device of this type having dust-excluding caps interlocked against rotation with the knuckle and constituting bearings for the ends of the knuckle.

A further object of the invention is to provide a structure of the character above mentioned, in which the dust-excluding caps serve, at once, to retain the bushings within the knuckle and to form bearings for the knuckle.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings, Figure 1 shows the invention in side elevation; Fig. 2 is a longitudinal section; Fig. 3 is a perspective of the upper dust-excluding cap; and Fig. 4 is a perspective of the lower dust-excluding cap.

In the accompanying drawings, the numeral 1 designates an axle, having, as usual, arms 2, terminated in alined bearings 3 and 4. There is a transverse shoulder 5 upon the lower face of the upper bearing 3, a similar shoulder 6 being fashioned upon the upper face of the lower bearing 4.

The numeral 7 indicates the movable axle end, the same being provided with a tubular knuckle 8, the bore of which is designated by the numeral 9. The extremities of the bore 9 of the knuckle are enlarged in diameter as indicated at 10 to receive bushings 11.

A dust-excluding cap, denoted generally by the numeral 12, is interposed between

the upper end of the knuckle 8 and the upper arm 2. In its upper face, the cap 12 is fashioned with a transverse shoulder 14, the shoulders 14 and 5 constituting interengaging elements preventing the cap 12 from rotating upon the bearing 3. At its periphery, the cap 12 is provided with a depending flange 15 surrounding the upper end of the knuckle 8, the construction being such that the upper end of the knuckle is journaled for rotation within the cap 12.

The invention further includes a lower cap 16 which is interposed between the lower end of the knuckle 8 and the lower arm 2. The cap 16 constitutes a thrust bearing for the knuckle 8, and is provided with a shoulder 17 in its lower face, the shoulders 17 and 6 constituting interengaging elements serving to prevent the cap 16 from rotating upon the bearing 4. The cap 16 is equipped with a reduced neck 18 received rotatably within an enlarged portion 19 of the bore 9 of the knuckle 8.

The numeral 20 designates generally, a spindle which is extended through the bearings 3 and 4, the spindle 20 being reduced and threaded at its lower end, as indicated at 21, the end 21 being threaded into the bearing 4. A nut 22 is applied to the threaded end 21 of the spindle, the nut bearing against the lower face of the bearing 4. Adjacent its upper end, the spindle 20 is provided with a shoulder 23 engaging the upper face of the bearing 3, the shoulder 23 being provided with wrench faces, as indicated most clearly in Fig. 1, whereby the spindle 20 may be rotated to cause the threaded end 21 thereof to engage with the bearing 4.

Fashioned in the upper end of the spindle 20 is an oil chamber 24 communicating with an axial duct 25, extended laterally through the spindle and opening into a superficial, longitudinal groove 26. Threaded into the chamber 24 is an oil cup 27 having superficial wrench faces 28. In the interior of the oil cup 27 is a circumscribing groove 29, the ends of which define shoulders between which is slidably mounted a valve disk 30, thrust downwardly by means of a compression spring 31, bearing against the upper end of the groove 29, to thrust the valve disk 30 against the lower end of the groove. Located within the spring 31 is a link 32, connected with the valve disk 30, and pivotally connected with

the under side of a cap 33 which bears against the upper end of the oil cup 27.

Owing to the fact that the upper end of the knuckle 8 is received within the flange 15 of the cap 12, the entrance of dust into the interior of the knuckle will be avoided. Furthermore, owing to the fact that the lower cap 16 is equipped with the reduced neck 18 fitting within the knuckle 8, the entrance of dust into the knuckle, at the lower end of the knuckle, will be avoided. Since the caps 12 and 16 are provided, respectively, with the shoulders 14 and 17, engaging respectively with the shoulders 5 and 6, the caps will be held against rotation, the caps constituting bearings upon which the ends of the knuckle 8 are journaled. The caps 12 and 16 engage the ends of the bushings 10, and constitute means for retaining the bushings within the knuckle.

As will be understood readily, the valve disk 30 may be manipulated, the oil in the oil chamber 24 flowing downwardly through the duct 25 and thence into the groove 26, an efficient and thorough lubrication of the knuckle 8, as the same rotates upon the spindle 20, being thereby effected.

The device is so constructed that a knuckle which has been worn at its ends, and the bore of which has been unduly enlarged, through wearing, may be renewed and made serviceable. As will be understood readily, the caps 12 and 16 not only constitute dust-excluding members, but, at the same time, they constitute means in which the knuckle is journaled. Further, the caps 12 and 16 serve to take up any space existing between the ends of the knuckle 8 and the bearings 3 and 4, a longitudinal reciprocation of the knuckle 8 upon the spindle 20 being thereby avoided.

Having thus described the invention, what is claimed is:—

1. In a device of the class described, a

member having arms; a part having a knuckle received between the arms; upper and lower dust-excluding caps interposed between the ends of the knuckle and the arms, the upper cap having a flange engaging the outer face of the knuckle; interengaging elements upon the caps and the arms preventing a rotation of the caps; and a spindle engaged with the arms, with the caps and with the knuckle. 45 50

2. In a device of the class described, a member having arms; a part having a knuckle received between the arms; upper and lower dust-excluding caps interposed between the ends of the knuckle and the arms, the upper cap having a flange engaging the outer face of the knuckle and the lower cap having a reduced neck extended into the knuckle; interengaging elements upon the caps and upon the arms coöperating to prevent a rotation of the caps; and a spindle engaged with the arms, with the caps and with the knuckle. 60 65

3. In a device of the class described, a member having arms; a part having a knuckle received between the arms; upper and lower dust-excluding caps interposed between the ends of the knuckle and the arms, the upper cap having a flange engaging the outer face of the knuckle and the lower cap having a reduced neck entering the knuckle; interengaging elements upon the caps and upon the arms preventing rotation of the caps; bushings within the knuckle and abutting against the caps; and a spindle engaged with the arms, with the caps, with the bushings and with the knuckle. 75 80

In testimony that I claim the foregoing as my own, I have hereto affixed my signature in the presence of two witnesses.

RANDOLPH MENALCUS McGAHEE.
